(57) **CLAIM**

The ornamental design for a charging pile with two plugs, as shown and described.

DESCRIPTION

FIG. 1 is a front and top perspective view of a charging pile with two plugs design showing my new design.
 FIG. 2 is a front view of the charging pile with two plugs.
 FIG. 3 is a rear view of the charging pile with two plugs.
 FIG. 4 is a left view of the charging pile with two plugs.
 FIG. 5 is a right view of the charging pile with two plugs.
 FIG. 6 is a top view of the charging pile with two plugs; and,
 FIG. 7 is a bottom view of the charging pile with two plugs. The broken lines in the drawings depict portions of the charging pile with two plugs that form no part of the claimed design.
